INTERNAL COMBUSTION ENGINE FOR
AIRCRAFT

Clarence H. Wiegman, Williamsport, Pa., assignor,
by mesne assignments, to The Aviation Corporation,
New York, N. Y., a corporation of Delaware

Application June 10, 1939, Serial No. 278,415

8 Claims. (Cl. 123—56)

The present invention relates generally to internal combustion engines. More particularly the invention relates to that type of internal combustion engine which is designed primarily for mounting in the front portion of the fuselage of an airplane, and has the cylinders thereof disposed in two opposed substantially horizontal banks.

One object of the invention is to provide an internal combustion engine of this type which is generally of new and improved construction and has certain advantages over, and is more efficient than, previously designed engines of the same general character.

Another object of the invention is to provide an internal combustion engine of the opposed cylinder type in which the various parts thereof are arranged in a novel manner and are so designed and constructed that they may be readily dismantled in connection with maintenance, inspection or repair.

A further object of the invention is to provide an internal combustion engine of the type and character under consideration which includes simple and extremely efficient lubricating means for the rocker arms in the rocker boxes and is designed to provide maximum visibility for the pilot or operator of the airplane in which the engine is installed.

A still further object of the invention is to provide an internal combustion engine of the horizontal opposed cylinder type which is extremely light in weight and occupies but a small amount of space.

Other objects of the invention and the various advantages and characteristics of the present internal combustion engine will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a plan of an internal combustion engine embodying the invention;

Figure 1^a is a vertical longitudinal section on the line 1^a—1^a of Figure 1;

Figure 2 is a front view of the engine;

Figure 3 is a fragmentary horizontal section;

Figure 4 is a vertical transverse section taken on the line 4—4 of Figure 3 and illustrating in

detail the construction and design of the cylinders, the cylinder heads and the mechanism for operating the valves;

Figure 5 is a vertical longitudinal section taken on the line 5—5 of Figure 2 and showing the arrangement and design of the crank shaft and cam shaft of the engine;

Figure 6 is a vertical transverse section taken on the line 6—6 of Figure 5 and illustrating in detail the gearing whereby the cam shaft is driven from the crank shaft of the engine;

Figure 7 is an inner face view of the casing at the rear end of the engine crank case for enclosing the cam shaft gearing;

Figure 8 is a perspective of the two castings which serve to form the crank case and cylinders of the engine;

Figure 9 is a perspective of the sump casting at the bottom of the crank case;

Figure 10 is a perspective of one of the cylinder heads;

Figure 11 is an enlarged end view showing one of the rocker boxes at the outer ends of the cylinder heads without its cover and illustrating in detail the arrangement and design of the valve actuating rocker arms;

Figure 12 is an inner face view of one of the covers for the rocker boxes;

Figure 13 is an enlarged section of one of the tappets for actuating the push rods of the engine; and

Figure 14 is a vertical section on the line 14—14 of Figure 13.

The internal combustion engine which is shown in the drawings constitutes the preferred embodiment of the invention. It is designed primarily to form the propulsion medium for an airplane and comprises as the main or essential parts thereof a pair of complementary crank case and cylinder forming castings 15, a set of cylinder heads 16, a crank shaft 17, a set of pistons 18, a cam shaft 19, and a sump casting 20.

The castings 15 are complementary and, as shown in the drawings, are positioned in opposed relation. The inner parts of the castings 15 define the engine crank case and are shaped to form a pair of opposed horizontally elongated substantially parallel outer side walls 21, a pair of horizontally aligned abutting front walls 22, a pair of horizontally aligned intermediate walls 23, and a pair of horizontally aligned abutting rear walls 24. Through-bolts 25 are fixed in the inner faces of the side, intermediate and rear walls of one of the castings and these bolts extend through aligned holes in the front, inter-

50 a pair of horizontally aligned intermediate walls 23, and a pair of horizontally aligned abutting rear walls 24. Through-bolts 25 are fixed in the inner faces of the side, intermediate and rear walls of one of the castings and these bolts extend through aligned holes in the front, inter-

mediate and rear walls of the other casting and serve removably to secure the two castings 15 in abutting relation. The upper inner portions of the front walls 22 are shaped to form a pair of opposed semi-cylindrical recesses 26 and these together form a bearing opening for the front end of the crank shaft 17. The upper central portions of the intermediate walls 23 are shaped to form a pair of opposed semi-cylindrical recesses 27 and these are longitudinally aligned with the recesses 26 in the front walls 22 and together define an opening for an inboard central bearing for the crank shaft. The upper inner portions of the rear walls 24 of the inner parts of the castings 15 are shaped to form a pair of complementary opposed semi-cylindrical recesses 28 and these are longitudinally aligned with the recesses 26 and 27 and form a bearing opening for the rear end of the crank shaft 17. The cam shaft 19 of the engine is disposed beneath and in parallel relation with the crank shaft and is driven by the latter, as hereinafter described. The inner lower portions of the front walls 22 are shaped to form a pair of opposed complementary semi-cylindrical recesses 29 and these constitute or form a bearing opening for the front end of the cam shaft. The inner lower portions of the intermediate walls 23 are shaped to form a pair of opposed complementary semi-cylindrical recesses 30 and these are aligned with the recesses 29 and form an opening for a central inboard bearing for the cam shaft. The inner lower portions of the rear walls 24 of the inner parts of the castings 15 are shaped to form a pair of opposed complementary semi-cylindrical recesses 31 and these are longitudinally aligned with the recesses 29 and 30 and together form a cylindrical bearing opening for the rear end of the cam shaft. In addition to the front, intermediate and rear walls 22, 23 and 24, the inner crank case forming parts of the castings 15 embody or include horizontally extending webs 32. These webs extend between the lower portions of the front, intermediate and rear walls and are joined to the lower portions of the side walls 21. They serve to cross-connect the various walls constituting the inner crank case forming parts of the two castings 15 and operate to strengthen and lend rigidity to the castings 15 as a whole. The inner ends of the webs 32 of one casting are preferably spaced from the inner ends of the webs of the other casting. At the lower corners of the side walls 21 four laterally extending lugs 33 are provided. These embody vertically extending bolt holes therethrough and are adapted for use in mounting the engine in place. The bottom of the crank case which is defined by the side, front, intermediate and end walls is closed or sealed by means of the sump casting 20. The latter is disposed beneath the inner parts of the complementary castings 15 and forms a reservoir or tank for a column of oil or other lubricant for the operating parts of the engine. The upper margin of the casting 20 embodies an integral horizontally extending flange 34 and this flange fits against and is secured by vertical bolts to a correspondingly shaped bottom flange 35. The latter is formed integrally with and as a part of the bottom margins of the side, front and rear walls 21, 22 and 24 of the inner parts of the castings 15. The top or upper end of the crank case is normally closed by a rectangular upwardly bulged cover plate 36. This plate embodies an outwardly extending marginal flange which fits flatly against a corresponding-

ly shaped flange 37 on the inner parts of the castings 15 and is removably secured to said flange 37 by vertical bolts 38. The cover plate 36 and the sump casting 20 assist the through-bolts 38 in securing together and holding against separation the castings 15. When it is desired to separate the castings in connection with maintenance, repair or inspection of the operating parts of the engine, it is only necessary to remove the cover plate 36 and the sump casting 20 and then release the through-bolts 38 by removing the nuts on the threaded ends thereof. Inspection of or access to the crank shaft 17 and the cam shaft 19 is obtained by removing the bolts 38 and raising the cover plate 36.

The outer parts of the two complementary castings 15 are formed integrally with the inner parts and are shaped to form four horizontally extending cylinders 39 as shown in Figures 1 and 20 8. There are two cylinders at each side of the engine, the cylinders at one side of the engine being arranged in opposed relation with those at the other side. The cylinders 39 are longitudinally bored from one end thereof to the other 25 and communicate with the interior of the crank case by way of circular openings in the side walls 21. They slidably support pistons 40 and are separated by spaces 41. Annular fins 41 surround and are formed integrally with the cylinders 39. These fins are spaced apart laterally 30 and constitute heat exchange or transfer means for use in air cooling of the cylinders. They surround the central and outer end portions of the cylinders and are of substantially uniform diameter. The adjacent portions of the fins on the central inner portions of the cylinders are formed integrally with one another, as shown in Figures 35 1 and 3, and as a result the castings 15 are materially strengthened without any substantial increase in weight. The fins 41 around the outer 40 ends of the cylinders are not cross-connected or attached and hence such outer ends of the cylinders are free or independent of one another and permitted to expand or contract each independently of the others.

The cylinder heads 16 correspond in number to, and are associated respectively with the outer ends of, the cylinders 39. They are in the form of metal castings and consist of upper inner end parts 42, lower outer end parts 43, and intermediate parts 44 between the upper end portions of the outer end parts and the lower portions of the inner end parts. The inner end parts 42 are bolted or otherwise removably secured in sealed relation against the outer ends of the cylinders 39 and are outwardly bulged or dome-shaped. They define combustion chambers 45 at the outer ends of the cylinders and have annular laterally spaced integrally formed fins 46 for cooling purposes. The central portions of the upper inner end parts 42 of the cylinder heads have outwardly and upwardly inclined internally threaded holes 47. These holes communicate with the combustion chambers 45 and serve as seats for the inner ends of a set of spark plugs 48. By reason of the location and angularity of the holes 47 the spark plugs 48 are located for the most part outwards of the cylinders and hence do not interfere with the vision of the pilot or operator of the airplane in which the engine is mounted. The portions of the upper inner end parts 42 that are disposed beneath the spark plugs 48 have intake ports 49 and exhaust ports 50 therein. The intake ports 49 are controlled by mushroom type valves 51 and the exhaust ports 50 are

controlled by means of mushroom type exhaust valves 52. The intermediate parts 44 of the cylinder heads 16 have cooling fins 53 and are cored to form inlet passages 54 and exhaust passages 55. The inlet passages extend upwardly from the bottom portions of the intermediate parts 44 and lead upwardly to and communicate with the inlet ports 49. The lower ends of the inlet passages 54 extend through the bottom portions of the intermediate parts of the cylinder heads and are provided with depending inlet sleeves 56. The exhaust passages 55 are positioned in side by side relation with the inlet passages 54 and communicate with and lead downwardly from the exhaust ports 58. The lower ends of the exhaust passages 55 are provided with depending exhaust sleeves 57. As shown in Figure 3 the inlet passages 54 in the cylinder heads for the fore or front cylinders are located in the rear portions of the intermediate parts 44 and the inlet passages in the cylinder heads for the aft or rear cylinders are located in the front portions of the intermediate parts of the cylinder heads. As shown in Figure 3, the exhaust passages 55 in the cylinder heads for the fore cylinders are located in the front portions of the intermediate parts 44 and the exhaust passages 55 in the cylinder heads for the aft or rear cylinders are located in the rear portions of the intermediate parts of the cylinder heads. The lower outer end parts 43 of the cylinder heads are positioned outwardly of, and project below the sleeves 56 and 57. They are formed integrally with the intermediate parts 44 and define rocker boxes 58. The latter have open outer ends and these are normally closed by means of covers 59. The covers are removably secured in place by bolts 60 and when removed provide access to the interior of the rocker boxes 58. The valves 51 for controlling the intake ports have outwardly extending stems which extend through and slide within sleeves 61 which project into the upper ends of the rocker boxes 58, as shown in Figure 4. Compression springs 62 extend around the outer projecting ends of the stems of the valves 51 and serve to urge the valves into seated relation with the inlet ports 49. Said springs 62 extend between and abut against washers 63 at the outer ends of the stems of the valves 51 and shoulders around the outer ends of the sleeves 61. The valves 52 for controlling the exhaust ports 58 are located in side by side relation with the valves 51 and embody rearwardly and downwardly extending stems which fit slidably in sleeves 64 in the upper portions of the intermediate parts 44 of the cylinder heads 16 and project into the upper ends of the rocker boxes 58. Compression springs 65 extend around the outer projecting ends of the stems of the valves 52 and serve to urge such valves into closed or seated relation with the exhaust ports 58.

The valves 51 and 52 for controlling the inlet and exhaust ports 49 and 58 respectively are unseated in proper timed relation by means of the cam shaft 19 and mechanism comprising pairs of tappets 66 and 68, pairs of push-rods 67 and 69, and pairs of rocker arms 69 and 70. The cam shaft 19 is located in the lower portion of the crank case and is journaled in a front bearing 71, an inboard intermediate bearing 72, and a rear bearing 73. The bearing 71 is suitably secured within the opening which is defined by the semi-cylindrical recesses 29 in the inner lower portions of the front walls 22 of the inner parts of the castings 15. The intermediate inboard bearing 72

fits within the opening which is defined by the semi-cylindrical recesses 28 and the rear bearing 73 fits and is secured within the opening which is defined by the semi-cylindrical recesses 51. The tappets 66, the push-rods 67, and the rocker arms 69 serve to actuate or unseat the intake valves 51. The tappets 66 are slidably mounted in horizontally extending, transversely disposed tubular enlargements 74, and are positively moved or slid outwards during rotation of the cam shaft 19 by lobes 75 on said shaft. The enlargements 74 are formed integrally with, and constitute parts of, the horizontally extending webs 32. The inner ends of the tappets 66 are in the form of enlarged heads and these, as shown in Figure 13 bear against the lobes 75. The push-rods 67 are disposed in and extend loosely through shroud tubes 76 which extend horizontally between the crank case and the lower inner portions of the lower outer end parts 43 of the cylinder heads 16 and are positioned beneath the cylinders 39. The inner ends of the tubes 76 fit within holes in the lower portions of the side walls 21 of the inner parts of the castings 15 and communicate with the outer ends of the tubular enlargements 74. The outer ends of the tubes 76 are seated in holes in the lower portions of the outer lower end parts 43 of the cylinder heads and are in communication with the lower portions of the rocker boxes 58. The push-rods 67 are longer than the shroud tubes 76 and have the inner ends thereof arranged in abutment with the outer ends of the tappets 66. The outer ends of the push-rods 67 project into the rocker boxes and, as shown in Figure 4, have cup-shaped enlargements at their outer extremities. The rocker arms 69 extend substantially vertically and are disposed in the rocker boxes 58. The central portions of the rocker arms 69 are journaled on horizontally extending stub shafts 78 and these shafts, as shown in Figure 11, are mounted in bearings 79 in the side portions of the outer lower parts 43 of the cylinder heads 16. The upper ends of the rocker arms 45 bear against the outer ends of the stems of the intake valve 51 and the lower ends of the arms embody adjusting screws 80 which bear against the cup-shaped enlargements at the outer ends of the push rods 67. When the lobes 75 on the cam shaft strike against the inner ends of the tappets 66 they force the tappets together with the push-rods 67 outwards in the direction of the rocker boxes 58. Such movement on the part of the tappets and push-rods operates so to swing the rocker arms 69 as to unseat the intake valves 51. The tappets 66, the push-rods 68, and the rocker arms 70 are located or disposed in side by side relation with the tappets 66, the push-rods 67 and the rocker arms 69 and operate in response to rotation of the cam shaft 19 to unseat the exhaust valves 52. The tappets 66 are slidably mounted in horizontally extending transversely disposed enlargements 81 and have at the inner end thereof enlarged hardened heads which abut against lobes 82 on the cam shaft 19. The enlargements 81 are positioned in parallel relation with the enlargements 74 and are formed integrally with and as parts of the webs 32. The push-rods 68 are positioned in parallel relation with the push-rods 67 and extend through and fit loosely within shroud tubes 83. The latter underlie the cylinders 39 and extend between the lower portions of the side walls 22 and the inner lower portions of the outer lower end parts 43 of the cylinder heads 16. The inner ends of the

tubes 83 communicate with the outer ends of the tubular enlargements 81 and the outer ends of such tubes communicate with the lower portions of the rocker boxes 88. The inner ends of the push-rods 68 abut against the outer ends of the tappets 66 and the outer ends of said push-rods project into the rocker boxes, as shown in Figure 2. The rocker arms 70 extend substantially vertically and are disposed in the rocker boxes. The central portions of the rocker arms 70 are mounted on the stub shafts 78 and the lower ends of said rocker arms abut against the outer ends of the push-rods 68. The upper ends of the rocker arms 70 abut against the outer ends of the stems of the exhaust valves 52 and operate to unseat such valves when the tappets 66 and the push-rods 68 are shifted outwards in response to the action of the lobes 82 during drive or rotation of the cam shaft 19.

The crank shaft 17 is connected to drive the cam shaft 19 by way of a pair of gears 84 and 85 and is journaled in a front bearing 86, an intermediate inboard bearing 87, and a rear bearing 88. The front bearing 86 fits within the opening which is defined by the semi-cylindrical recesses 26 in the upper inner portions of the front walls 22 of the inner parts of the castings 15 and the intermediate inboard bearing 87 fits within the opening which is defined by the semi-cylindrical recesses 27. The rear bearing 88 overlies the rear bearing 73 for the cam shaft 19 and fits within the opening which is defined by the semi-cylindrical recesses 28 in the rear walls 24. The central portion of the crank shaft embodies crank arms 89 and these arms, as shown in Figure 3, are connected by connecting rods 90 to transversely extending wrist pins 91 in the inner ends of the pistons 18. Successive explosions in the combustion chambers 48 at the outer ends of the cylinders operate as well understood in the art to move inwards the pistons and effect rotation of the crank shaft. The front end of the crank shaft projects beyond the front bearing 86 and carries a hub 92 for a propeller (not shown). The gear 84 is mounted on the rear end of the crank shaft and, as shown in Figure 5, is disposed outwards or rearwardly of the rear walls 24 of the inner parts of the castings 15 and is in mesh with the gear 85. The latter is suitably mounted on, and fixed to, the rear end of the cam shaft 19 and is also disposed rearwards or outwardly of the rear walls 24. When the crank shaft is rotated as the result of reciprocation of the pistons, the gears 84 and 85 operate to rotate or drive the cam shaft 19. A plate-like casing 93 serves to cover the gears 84 and 85. This casing is bolted to the rear walls 24 and serves with the through-bolts 25, the cover plate 36, and the sump casting 20, releasably or removably to secure the castings 15 in opposed connected relation.

A magneto 84 for supplying current to the spark plugs 48 is mounted on the upper rear portion of the casing 93 by means of bolts or other connecting devices, and is arranged so that the armature shaft thereof is coaxially positioned with respect to the crank shaft 17. The front end of the magneto armature shaft is provided with a tapered spindle 85 and this is keyed to the hub of the cam shaft driving gear 84.

The engine is lubricated by means of an oil pump 86. This pump comprises a casing 87 and a pair of meshing gears 88 and 89 in the casing. The casing, as shown in Figure 7, is formed as an integral part of the plate-like 75

casing 88 and is located at the lower portion of the latter. The gears 88 and 89 are rotatably mounted in the casing 87. The gear 88 is keyed to the rear extremity of the cam shaft 19 and operates during drive of such shaft to rotate the gear 89 and create suction in one side of the casing 87 and pressure in the other side of the casing. The suction side of the pump 86 is connected to receive oil from the bottom of the sump casting 20 by way of a cored passage 100. This passage is formed in the rear end wall of the sump casting and extends substantially vertically, as shown in Figure 5. The outlet or pressure side of the pump 86 communicates with a longitudinal passage 101 in the cam shaft 19 by way of a duct 102. When the pump is driven as the result of rotation of the cam shaft oil is drawn into the suction side of the pump casing 87 from the bottom of the sump casting 20 through or via the cored passage 100. After being placed under pressure the oil flows through the duct 102 into the longitudinal passage 101 in the cam shaft. The cam shaft bearings 71, 72 and 73 receive oil from the passage 101 by means of cross-ports in the cam shaft. The bearings 86, 87 and 88 for the crank shaft receive oil for lubricating purposes by way of upwardly extending oil passages 103 in the front, intermediate and rear walls of the complementary crank case and cylinder forming castings 15. These passages, as shown in Figure 5, lead upwardly from the openings for the cam shaft bearings and receive oil from such bearings. In order to lubricate the tappets, push-rods and rocker arms constituting the valve actuating mechanism of the engine, the outer ends of the tubular enlargements 74 are provided with upwardly facing holes 104 and the outer ends of the tubular enlargements 81 are provided with downwardly facing holes 105, as shown in Figure 14. When the engine is in operation oil in the crank case is splashed into the holes 104 and flows through the shroud tubes 76 into the lower portions of the rocker boxes 88. After lubricating the bearing forming portions of the rocker arms, the oil returns to the sump casting 20 by way of the shroud tubes 83 for the push-rods 68 and the downwardly facing holes 105 in the outer ends of the tubular enlargements 81. In order properly to control the lubricant in the rocker boxes 88 vertically extending dams 106 are provided. These dams are formed by abutting webs which are formed integrally with the lower portions of the rocker box cover 59 and the lower outer end parts 43 of the cylinder heads 16. As shown in Figures 4 and 11, the dams 106 extend upwardly from the bottom of the rocker boxes and terminate at their upper ends adjacent to the rocker arm supporting shafts 78. As a result of the provision of the dams 106 the lubricant which is introduced into the rocker boxes flows around the lower ends of the rocker arms 68 and then over the dams and around the lower ends of the rocker arms 70 and thence back to the sump casting 20 via the shroud tubes 83 and the holes 105. The upper ends of the rocker arms are lubricated by oil vapor. The rocker boxes are air tight except for the passages afforded by the shroud tubes. The shroud tubes 83 and the downwardly facing holes 105 constitute vents for the rocker boxes whereby pressure and excess oil in the rocker boxes are vented into the sump casting 20. As the result of elimination of pressure in the rocker boxes by the aforementioned

tioned venting arrangement proper lubrication of the rocker arms is obtained and it is not necessary to vent the boxes to the atmosphere surrounding the cylinder heads 16. With the present form or type of rocker arm lubricating means there is no loss of lubricant.

Gaseous fuel is supplied to the sleeves 56 for passage to the combustion chambers 45 via the inlet passages 54 and the inlet ports 49 by way of a carburetor 107, a distributor manifold 108, and a set of intake pipes 109. The carburetor 107 is connected to and is disposed under the bottom of the sump casting 28 and embodies a gaseous fuel outlet in communication with the distributor manifold 108. The latter is formed as an integral part of the sump casting 28, as shown in Figures 4, 5 and 9, and comprises a vertically extending conduit 110, an enlarged header 111 in the upper end of the conduit 110, and horizontal tubes 112 leading from the header 111. The tubes, as shown in Figure 9, extend through the sides of the sump casting 28 and are provided with discharge sleeves 113. The pipes 109 underlie the cylinders 38 and project outwardly from the sump casting 28. The inner ends of the tubes are connected by flexible couplings 114 to the discharge tubes 113 at the outer ends of the tubes 112. The outer ends of the pipes 109 extend upwardly, as shown in Figures 2 and 4, and are connected by flexible couplings to the inlet sleeves 56. The tubes 112 are all the same in length and the pipes 109 are also all the same in length. As a result of this, and because the inlet passages 54 are all the same in length gaseous fuel travelling to each combustion chamber travels the same distance as the fuel which travels to the other combustion chambers and high efficiency of the engine is thus obtained. By having the distributor manifold disposed in the sump casting 28 the gaseous fuel is subjected to the heat of the oil in the casting prior to passage into the combustion chambers in the cylinder heads.

The products of combustion emanating from the exhaust sleeves while the exhaust valves 52 are open, are discharged downwardly by means of short substantially straight exhaust pipes 116. These pipes are suitably connected at their upper ends to the exhaust sleeves 57. By having the pipes 109 positioned beneath the cylinders and the exhaust pipes 116 disposed in a depending manner from the intermediate parts 44 of the cylinder heads 16 neither set of pipes obstructs the vision of the pilot of the airplane in which the engine is mounted. By having the receiving upper ends of the exhaust pipes disposed adjacent to the upper outer ends of the fuel supply pipes 109 the gaseous fuel entering the intake passages 54 is subjected to heat from the exhausted products of combustion.

The herein described engine because of the arrangement and design of the various parts thereof may be readily dismantled and is extremely efficient for its weight. It occupies but a comparatively small space and provides maximum vision for the pilot of the airplane in which the engine is mounted. In addition to the foregoing the present engine is characterized by the fact that the rocker arms are efficiently and effectively lubricated without venting the rocker boxes to atmosphere and the cylinder heads are so designed that they are interchangeable. By having the cylinder and crank case forming parts of the engine in the form of two complementary castings, the engine embodies but a small number

of parts and removal of the crank and cam shafts is extremely simple.

Whereas the invention has been described in connection with a four cylinder opposed type internal combustion engine, it is to be understood that it is also capable of being embodied in a two cylinder opposed type engine or an engine having cylinder banks of more than two cylinders each. It is also to be understood that the invention is not to be restricted to the details set forth since these may be modified within the scope of the appended claims without departing from the spirit and scope of the invention.

Having thus described the invention, what I claim as new and desire to secure by Letters Patent is:

1. An internal combustion engine including a pair of complementary horizontally extending castings disposed in side by side and abutting relation and having the inner parts thereof shaped to form an open top and open bottom crank case and comprising laterally spaced side walls and pairs of aligned and abutting front and rear walls, and having the outer parts thereof formed integrally with said inner parts respectively and shaped to form oppositely extending cylinders with their inner ends in communication with the crank case interior, horizontal through-bolts extending longitudinally through the front walls and horizontal through-bolts extending longitudinally through the rear walls for removably securing the two castings together, a separately formed sump for lubricant disposed beneath and serving to close the open bottom of the crank case and having a top flange in abutment with the bottom marginal portions of the inner parts of the two castings and connected removably thereto by vertical bolts, a separately formed cover plate for closing the open top of the crank case provided with a marginal flange in abutment with the upper marginal portions of said inner parts of the castings and connected removably thereto by means of vertical bolts, a crank shaft extending through the crank case in parallel relation with the side walls and having its front end journaled in a front bearing between the front walls and its rear end journaled in a rear bearing between the rear walls, and pistons slidably mounted in the cylinders and connected operatively to the cranks of the crank shaft.
2. An internal combustion engine including a pair of complementary horizontally extending castings disposed in side by side abutting relation and having the inner parts thereof shaped to form an open top and open bottom crank case and comprising laterally spaced side walls and pairs of aligned and abutting front, intermediate and rear walls, and having the outer parts thereof formed integrally with said inner parts respectively and shaped to form oppositely extending cylinders with their inner ends communicating with the crank case interior at points between said front, intermediate and rear walls, horizontal through-bolts extending longitudinally through said pairs of walls respectively and serving removably to secure the two castings together, a separately formed sump for lubricant disposed beneath and serving to close the open bottom of the crank case and having a marginal flange at the upper part thereof connected removably to the bottom marginal portions of the inner parts of the two castings by vertical bolts, a separately formed cover plate for closing the open top of the crank case positioned in abutment with the upper marginal portions of said inner parts of

the castings and secured removably thereto by means of vertical bolts, a crank shaft extending through the crank case in parallel relation with the side walls and having its front portion journaled in a front bearing between the front walls, its intermediate portion journaled in an intermediate bearing between the intermediate walls and its rear portion journaled in a rear bearing between the rear walls, and pistons slidably mounted in the cylinders and connected by connecting rods to the cranks of the crank shaft.

3. An internal combustion engine including a pair of complementary horizontally extending castings disposed in side to side and abutting relation and having the inner parts thereof shaped to form an open top and an open bottom crank case and comprising laterally spaced side walls and pairs of aligned and abutting front and rear walls, and having the outer parts thereof formed integrally with said inner parts respectively and shaped to form oppositely extending cylinders with their inner ends in communication with the crank case interior, horizontal through-bolts extending longitudinally through the front walls and horizontal through-bolts extending longitudinally through the rear walls for removably securing the two castings together, a separately formed sump for lubricant disposed beneath and serving to close the open bottom of the crank case and removably secured by vertical bolts to the bottom portions of the inner parts of the two castings, a separately formed cover-plate for closing the open top of the crank case positioned in abutment with the upper portions of the inner parts of the castings and secured removably thereto by vertical bolts, vertically spaced crank and cam shafts extending horizontally through the crank case in parallel relation with the side walls and journaled in bearings between the front walls and bearings between the rear walls of the two castings, pistons slidably mounted in the cylinders and connected operatively to the cranks of the crank shaft, gearing for driving the cam shaft from the crank shaft disposed exteriorly of the crank case and positioned adjacent one pair of abutting walls, a casing for the gearing positioned in abutment with the last mentioned pair of walls, and bolts extending through the casing and said last mentioned walls and serving with said casing to assist the through-bolts, sump and cover plate in removably securing the castings together.

4. An internal combustion engine including a pair of complementary horizontally extending castings disposed in side by side and abutting relation and having the inner parts thereof shaped to form an open top and open bottom crank case and comprising laterally spaced side walls, pairs of aligned and abutting front and rear walls and opposed horizontal webs projecting inwardly from the lower portions of the side walls and extending between and joined to the front and rear walls and having the outer parts thereof formed integrally with said inner parts respectively and shaped to form opposed cylinders with the inner ends thereof communicating with the crank case interior at points above said webs, horizontal through-bolts extending longitudinally through the front walls and horizontal through-bolts extending longitudinally through the rear walls for removably securing the two castings together, a separately formed sump for lubricant disposed beneath and serving to close the open bottom of the crank case and secured removably to the bottom portions of the inner

parts of the castings by vertical bolts, a cover plate for closing the open top of the crank case secured removably to the top portions of said inner parts of the castings by vertical bolts, vertically spaced crank and cam shafts extending horizontally through the crank case in parallel relation with the side walls and journaled in bearings between the front walls and bearings between the rear walls, pistons slidably mounted in the cylinders and connected operatively to the cranks of the crank shaft, and valve mechanism comprising horizontally extending cam shaft actuated tappets slidably mounted in the webs.

5. An internal combustion engine comprising an open bottom crank case with laterally spaced side walls, opposed horizontally disposed cylinders connected to and extending outwardly from the side walls and having the inner ends thereof in communication with the crank case interior, individual cylinder heads connected to the outer ends of the cylinders respectively and embodying upper inner end parts forming combustion chambers for the cylinders, lower outer end parts forming rocker boxes, and intermediate parts extending between the inner and outer end parts and having side by side intake and exhaust passages leading to the combustion chambers and extending through their bottom portions, a crank shaft extending through the crank case, pistons slidably mounted in the cylinders and operatively connected to the cranks of the crank shaft, a separately formed sump for lubricant disposed beneath and serving to close the open bottom of the crank case, secured removably in place, and having in the central portion thereof an upstanding manifold with the lower end thereof leading through the sump bottom, a carburetor mounted beneath the sump bottom and having the fuel outlet thereof communicating with the lower end of the manifold, pipes for supplying gaseous fuel from the carburetor to the combustion chambers disposed beneath, and separate from, the cylinders and having the discharge ends thereof connected to the lower ends of the intake passages and their inlet ends connected to the upper end of the manifold, and separate or independent exhaust pipes adjacent the discharge ends of the first mentioned pipes connected to the lower ends of the exhaust passages and extending downwardly from the cylinder heads.

6. The combination with an internal combustion engine comprising a crank case with laterally spaced side walls and means forming an oil sump, opposed cylinders connected to and extending outwardly from the side walls and having the inner ends thereof in communication with the crank case interior, cylinder heads connected to the outer ends of the cylinders and shaped to form combustion chambers for the cylinders, intake and exhaust passages for said chambers and rocker boxes, a cam shaft journaled in the crank case, valves for controlling the intake and exhaust passages, and cam shaft actuated mechanism for operating the valves including horizontal push rods between the crank case and rocker boxes and pivotally mounted rocker arms in said boxes, of horizontal shroud tubes extending loosely around the push rods and extending between and communicating with the crank case and the rocker boxes, and means whereby oil is permitted to flow by gravity from the crank case through certain of the shroud tubes into the rocker boxes and from the

rocker boxes back to the crank case via other shroud tubes.

7. The combination with an internal combustion engine comprising a crank case with laterally spaced side walls and means forming an oil sump at the bottom thereof, opposed cylinders connected to and extending outwardly from the side walls and having the inner ends thereof in communication with the crank case interior, cylinder heads connected to the outer ends of the cylinders and shaped to form combustion chambers for the cylinders, intake and exhaust passages for said chambers and rocker boxes, a cam shaft journaled in the crank case, valves in the cylinder heads for controlling the intake and exhaust passages, and cam shaft actuated mechanism for operating the valves including horizontal push-rods between the crank case and rocker boxes and substantially vertically extending centrally pivoted rocker arms in said boxes, of horizontal shroud-tubes extending loosely around the push rods and extending between and communicating with the lower portions of the crank case and the rocker boxes, dams in the rocker boxes positioned between the rocker arms and extending from the bottom of the boxes to a point adjacent to the central portions of the rocker arm, and means whereby oil is permitted to flow from the crank case through certain of the shroud tubes into the rocker boxes for flow over the dams and from the rocker boxes back to the crank case via other shroud tubes.

8. The combination with an internal combustion engine comprising a pair of crank case forming castings secured together in abutting relation and embodying a pair of laterally spaced side walls and in addition opposed horizontal webs extending inwardly from the lower portions of the side walls and provided with tubular enlargements, opposed cylinders connected to and extending outwardly from the side walls, cylinder heads connected to the outer ends of the cylinders and shaped to form combustion chambers for the cylinders, intake and exhaust passages for said chambers and rocker boxes, a cam shaft journaled in the crank case, valves in the cylinder heads for controlling the intake and exhaust passages, and cam shaft actuated mechanism for operating the valves including tappets slidably mounted in said tubular enlargements, horizontal tappet actuated push-rods between the crank case and the rocker boxes, and pivotally mounted rocker arms in said boxes, of horizontal shroud tubes extending loosely around the push rods and extending between and communicating with the tubular enlargements and the rocker boxes, and means associated with said tubular enlargements forming upwardly and downwardly facing openings whereby oil in the crank case is permitted to flow through certain of the shroud tubes into the rocker boxes and from the rocker boxes back to the crank case via other shroud tubes.

CLARENCE H. WIEGMAN.
